UNITED STATES PATENT OFFICE.

THOMAS W. McDUGAL, OF CHICAGO, ILLINOIS, ASSIGNOR TO ARMOUR & COMPANY, OF CHICAGO, ILLINOIS, A CORPORATION OF ILLINOIS.

DESIGN FOR A CAKE OF SOAP.

46,508.

Specification for Design.

Patented Oct. 6, 1914.

Application filed May 2, 1914. Serial No. 836,028. Term of patent 7 years.

To all whom it may concern:

Be it known that I, THOMAS W. McDUGAL, a citizen of the United States, residing at Chicago, in the county of Cook and State of Illinois, have invented a new, original, and ornamental Design for Cakes of Soap, of which the following is a specification, reference being had to the accompanying drawings, forming part thereof.

Figure 1 of the drawing is a perspective view of a cake of soap showing my new

design; Fig. 2 is a face view of the cake of soap; and Fig. 3 is an end view of the cake.

I claim:

The ornamental design for a cake of soap, as shown.

THOMAS W. McDUGAL.
